Fig.3.

Fig.4.

Fig.6.

and the switch blade 19 in a manner more fully described hereinafter. A cam bar 31, having camming member 32 thereon, is rotatably attached to the base 11 at 33. The members 32 cooperate with sloping surfaces 30 on the camming platform 22 to tilt the platform about its pivot 24. The bar 31 has an upwardly extending projection 34 thereon which is disposed to be engaged by an internal web or projection 35 on the inside of the cup-shaped member 21. The cam bars 31 for all three switch units are connected together by a connecting link or bar 36.

The insulator stack 14 is fixed in position and supports a tank or container 37 which contains the control and latching mechanism for a switch unit. A top casting 37' on the tank 37 may function as a contact member for one end of the switch blade 19. A cover 38 may be provided on the casting 37' to protect the contact surface from snow and ice. As shown, the other end of the blade 19 engages the underside of the contact member 18 on the insulator stack 12. A terminal bushing 39 is provided on the top of the casting 37'.

As shown most clearly in Fig. 3, a control and latching mechanism is contained within the tank 37 which is provided with an insulating liner 41 and a top casting 42 which, as explained hereinbefore, is engaged by one end of the switch blade 19 when the blade is closed. The control and latching mechanism comprises a counting device 43 for counting closely successive interruptions of fault current flowing through the device, and may be of the type fully described in a copending application of J. M. Wallace, Serial No. 189,082, filed October 9, 1950, now Patent No. 2,752,453, issued June 26, 1956. The counting device 43 is suspended from the top casting 42 by insulating tubes or rods 44.

As described in the aforesaid copending application, the counting device 43 comprises a coil 45, one terminal of which is connected to the top casting 42 by a conductor 46 and the other terminal of which is connected to the terminal member 39 by a conductor 47. Thus, current may flow from the member 42 through the coil 45 to the terminal member 39. The member 39 may be connected to one of the power conductors in the distribution system.

As explained in the aforesaid copending application, when the coil 45 is energized by a predetermined value of current such as during an overload or short circuit, and is then deenergized by interruption of the current, a plunger 48 is raised a predetermined distance by the operation of the counting device. As described in the aforesaid application, the height of plunger 48 is adjustable to require 1 to 4 operations to engage and actuate the mechanism above it. Usually it is set to require two or more operations, so that if the line is reenergized and normal current flows after the first operation, the plunger 48 then moves down slowly to its original position without having actuated the mechanism of the switch. However, if fault current flows again when the line is reenergized, and the circuit is interrupted a second time, the plunger 48 is raised an additional amount. Thus, the plunger 48 is raised step by step by repeated interruptions of fault current until there has been a predetermined number of such interruptions within a predetermined time, and the plunger then engages a bell crank trigger 49 to release the switch blade, through a mechanism hereinafter described, and cause it to move to open position while the current is interrupted.

The bell crank trigger is pivotally attached to a supporting plate 51 by a pivot pin 52. The one arm of the bell crank trigger 49 normally engages a pin 53 at one end of a lever 54 which is pivotally supported on the plate 51 by a fixed pivot 55. The lever 54 carries a pivot pin 56 which is one of the supports for a generally triangular shaped lever 57. A toggle mechanism comprising a lever 58 pivotally connected to the lever 57 by a pin 59 and a lever 61 pivotally supported on the

casting 42 by a pin 62 constitutes the other point of support for the lever 57. The lever 57 is pivotally connected to a plunger 63 by a pin 64. The plunger 63 is slidably disposed in a guide portion 70 on the casting 42. The lower end of the plunger 63 is connected to a base plate 65 by a tension spring 60. The plate 65 is disposed underneath the counting device 43 which, as explained hereinbefore, is supported by the rods 44. A latch member 66 is slidably disposed in the upper end of the plunger 63 and is biased upwardly by a spring 67. The upper end of the latch 66 extends into an opening 68 in the switch blade 19. The latch 66 has a sloping surface 69 which permits the blade 19 to depress the latch 66 and ride over the latch when the blade is being closed. When the blade is in the closed position, the spring 67 forces the latch 66 into the opening 68 to retain the blade 19 closed unless the end of the blade is raised sufficiently to clear the latch 66 as will be explained more fully hereinafter.

The bell crank 49 is normally biased by a spring 71 to the position shown in the drawing. A hook 72 may be provided on the one arm of the trigger 49 to engage an edge of the plate 51 to limit the travel of the trigger in the direction in which it is biased by the spring 71.

A resetting lever 73 is pivotally attached to the plate 51 by a pin 74. The lower end of the lever 73 is connected to the lever 61 by a connecting link 75 which is attached to the lever 73 by a pin 76 and to the lever 61 by a pin 77. The lever 58 is attached to the lever 61 by a pin 78. A screw 79 is provided in the casting 42 to limit the upward travel of the outer end of the lever 61. Thus, the toggle mechanism may be properly adjusted.

As explained hereinbefore, the present isolating switch is utilized in conjunction with a reclosing circuit breaker to isolate a faulted circuit. A typical power distribution system is illustrated in Fig. 6 in which two load or feeder circuits are shown connected to a transformer by means of a transmission line and a reclosing circuit breaker located at a switch station which may be a considerable distance from the feeder circuits. A fault on either feeder circuit will cause the oil circuit breaker to go through its opening and reclosing cycle, thereby alternately energizing and deenergizing the transmission line.

As previously explained, the counting device 43 on the switch unit for the faulted phase of the feeder circuit is actuated by the energization and the deenergization of the feeder circuit. The counting device is so constructed that the plunger 48 is raised a step during the time that the oil circuit breaker is open to deenergize the feeder circuit. Thus, the plunger 48 engages the trigger 49 when the oil circuit breaker is open.

The actuation of the trigger 49 by the plunger 48 disengages an upper arm 80 of the trigger from the pin 53 in the lever 54. The disengagement permits the lever 54 to drop, thereby lowering the lever 57 which breaks the toggle mechanism. Once the toggle mechanism is released the spring 60 pulls the plunger 63 and the pin 64 downwardly to disengage the latch 66 from the switch blade 19 of the faulted phase. The downward movement of the triangular lever 57 is limited by the lower edge of the lever engaging the pin 52. Thus, the continued downward movement of the pin 64 caused by the spring 60 raises the pin 56 to raise the lever 54 and permit the spring 71 to bias the trigger arm 80 into position underneath the pin 53 in the lever 54.

When the one end of the switch blade 19 of the faulted phase is released from the latch 66, the spring 29 starts to rotate that blade. As the turning platform 21 rotates, the projection 35 on the platform 21 engages the projection 34 on the cam lever 31 thereby driving the cam lever. The connecting link 36 drives the cam levers for the switches for the other two phases. The camming members 32 on the other two phases tilt the camming platforms 22 of these switch units, thereby raising the ends of the switch blades to release them from their re-

spective latches. When the blades are released, the driving springs for these blades rotate them to their open position. One end of the connecting link 36 engages a buffer spring 81 to absorb the shock during opening of the blades.

In this manner, the switch blades for all three phases are opened quickly. However, as previously explained, the isolating switches are not required to interrupt current since they are opened during the period in which the reclosing oil circuit breaker is open, thereby deenergizing the feeder circuit.

As shown in Fig. 1, the upper end of a vertically disposed pipe or rod 82 is rotatably disposed in a cross member 83 which extends between two of the bases 11. An operating handle (not shown) may be provided on the lower end of the pipe 82 for manually operating the switch units. A ratchet device comprising a pivotally mounted pawl 84 is mounted on the top of the pipe 82. The ratchet pawl 84 drives an arm 85 which is connected to the link 36 which, as previously explained, connects the cam bars 31 for all three switch units. Stop members 86 and 87 are provided for resetting the ratchet device at the end of the closing and the opening operations of the operating mechanism. The switches are shown in their closed position in Fig. 1 and the pawl 84 has been disengaged from a shoulder 88 on a disc 89 secured to the arm 85. The disc 89 may function as a bearing member for one end of the arm 85. As shown in Fig. 5, an overcenter spring 90 may be provided to releasably retain the pawl 84 in the position to which it was last actuated.

As shown, the pawl 84 has been actuated into engagement with a shoulder 91 on the plate 89 by the stop member 86. Thus, the ratchet mechanism is set for opening the switch by means of the manually operable handle. It will be noted that the shoulder 88 is disengaged from the pawl 84. Therefore, the arm 85 is free to rotate in the pipe 82 during the automatic opening of the switch units in the manner hereinbefore described. In this manner, the switch units may be automatically opened even though the operating handle is locked in the closed position.

If it is desired to open the switch manually, the load should first be removed from the feeder circuit in order to avoid interrupting the load current. The pipe 82 is rotated to drive the arm 85 by means of the pawl 84 which is in engagement with the shoulder 91. As previously explained, the movement of the cam bars 31 causes the switch blades to be tilted by means of the camming action, thereby disengaging the blades from the latching members. When the blades are disengaged, the driving springs cause the blades to be opened quickly.

As previously explained, the arm 85 is free to rotate in the opening direction with respect to the pawl 84. Thus, the operator may continue to hold onto the operating handle while the opening of the switches is completed by the driving springs. He continues to rotate the pipe 82 until the pawl 84 engages the stop member 87, thereby setting the pawl for a closing operation of the switch.

If it is desired to close the switch units, the load should be disconnected from the feeder circuit before attempting to close the isolating switch. The operating handle is then utilized to rotate the pipe 82 to drive the arm 85 by means of the pawl 84 which engages the shoulder 88. As previously explained, the pawl 84 is disengaged from the shoulder 88 by the stop member 86 at the end of the closing operation. Thus, the ratchet mechanism is automatically set for opening the switches.

Referring to Fig. 3, it will be seen that the switch blade 19 will engage the resetting lever 73 when the blade is moved in the closing direction. The sloping surface 69 on the latch 66 of the unfaulted phase or phases permits the blade 19 to depress the latch 66 as the blade is being closed. The blade 19 of the faulted

phase actuates the lever 73 about its pivot point 74, thereby actuating the lever 61 about its pivot point 62 by means of the link 75 which connects the levers 73 and 61. The actuation of the lever 61 actuates the lever 57 about the pivot point 56 to raise the plunger 63 of the latching device for the faulted phase or phases, thereby resetting the latching device.

When the manually operable handle which drives the pipe 82 is released, the driving springs 29 return the switch blade 19 to the position shown in Fig. 3 in which the latch 66 is disposed in the opening 68 to hold the blades in the closed position. The resetting lever and the toggle mechanism are retained in the position shown in Fig. 3 since the toggle levers 58 and 61 are slightly past center. As previously explained, the toggle mechanism may be broken by the trigger lever 49 during automatic opening of the switch.

If desired, the latching device and the toggle mechanism may be reset by raising the end 92 of the lever 61 which is lowered when the toggle mechanism is tripped. The end 92 also functions as a signal or target to indicate which phase has been tripped during the fault conditions.

The switch blades 19 and their cooperating contact members may be so constructed that the blades are under a slight bending stress when closed, thereby providing good contact pressure. Since each blade is driven by an individual driving spring, the blades are opened very quickly. As previously explained, the opening of the switch blades takes place while the backup circuit breaker is open. Therefore, no arc is drawn during opening of the isolating switch. Since the contact members are separated while the backup breaker is open and the blades are moving away from the contact members very rapidly, they will be opened sufficiently to prevent an arc from being established even though the reclosing circuit breaker should reclose before the blades are completely open.

From the foregoing description, it is apparent that I have provided an isolating switch which is automatically opened under predetermined conditions without requiring current transformers, control relays, control power transformers, batteries and control wiring to control the operation of the switch. Thus, the cost of the present switch is reduced as compared with prior switches. Also, the cost of the switch is reduced as compared with an oil circuit breaker. Therefore, the present switch is particularly suitable for installation where feeder circuits are connected to a transmission line at remote points from the main switching station which controls the energization of the transmission line. Since the present switch is completely self-contained, it may be mounted on a pole or tower.

Since numerous changes may be made in the above-described construction, and different embodiments of the invention may be made without departing from the spirit and scope thereof, it is intended that all matter contained in the foregoing description or shown in the accompanying drawings shall be interpreted as illustrative and not in a limiting sense.

I claim as my invention:

1. In an electric switch, in combination, a base, a switch blade, insulating means rotatably supporting the blade substantially midway between its ends, said insulating means being pivotally mounted on said base to move the blade in a plane different from the plane of rotation, spring means for rotating said blade, latching means engaging one end of the blade for retaining the blade in the closed position, control means for releasing said latching means, and cam means for tilting said insulating means to move one end of said blade in one direction and the other end in the opposite direction to disengage it from the latch means independently of the control means.
2. In an electric switch, in combination, a base, a

switch blade, insulating means rotatably supporting the blade, said insulating means being movably mounted on said base to move the blade in a plane different from the plane of rotation, spring means for rotating said blade, latching means engaging one end of the blade for retaining the blade in the closed position, control means for releasing said latching means, means for actuating said insulating means to move one end of said blade in one direction and the other end in the opposite direction to disengage it from the latch means independently of the control means, and manually operable means for rotating said blade to store energy in said spring means.

3. In an electric switch, in combination, a base, a switch blade, insulating means rotatably supporting the blade substantially midway between its ends, said insulating means being pivotally mounted on said base to move the blade in a plane different from the plane of rotation, spring means for rotating said blade, latching means engaging one end of the blade for retaining the blade in the closed position, control means for releasing said latching means, cam means for tilting said insulating means to move one end of said blade in one direction and the other end in the opposite direction to disengage it from the latch means independently of the control means, manually operable means for closing said blade, and a reset lever for resetting said latching means, said lever being actuated by said blade when it is closed.

4. In an electric switch, in combination, a base, a switch blade, insulating means rotatably supporting the blade, said insulating means being movably mounted on said base to move the blade in a plane different from the plane of rotation, spring means for rotating said blade, latching means engaging one end of the blade for retaining the blade in the closed position, control means energized by the current flowing through said blade for releasing said latching means only when no current is flowing through the blade, and means for moving one end of the blade in one direction and the other end in the opposite direction in said different plane to disengage the blade from the latch means independently of the control means.

5. In an electric switch, in combination, a base, a switch blade, insulating means rotatably supporting the blade, said insulating means being pivotally mounted on said base to move the blade in a plane different from the plane of rotation, spring means for rotating said blade, latching means for retaining the blade in the closed position, control means disposed at one end of the blade and energized by the current flowing through the blade for releasing said latching means only when no current is flowing through the blade, cam means for disengaging the blade from the latch means independently of the control means, and manually operable means for closing said blade to reset said latch means.

6. In an electric switch, in combination, a base, a camming platform pivotally mounted on the base, a turning platform rotatably mounted on the camming platform, a switch blade carried by the turning platform, spring means for driving the turning platform to rotate the switch blade, latching means for retaining the blade in the closed position, control means disposed at one end of the blade and energized by the current flowing through the blade for releasing said latching means only when no current is flowing through the blade, cam means for tilting the camming platform to disengage the blade from the latch means independently of the control means, and manually operable means for closing said blade to reset said latching means.

7. In a polyphase switch structure, in combination, a rotatable switch blade for each phase, spring means for rotating each blade in a horizontal plane, cam means for moving each blade in a vertical plane, separate latching means for retaining each blade in the closed position, control means for releasing each latch means independently of other latch means, link means interconnecting the cam

means for all phases, said spring means for a released blade driving the cam means for the other blades to release them from their latch means independently of their control means, and manually operable means for closing said blades to reset said latch means, each latch means being reset by its blade independently of the latch means for the other blades.

8. In a polyphase switch structure, in combination, a rotatable switch blade for each phase, spring means for rotating each blade in a horizontal plane, cam means for moving each blade in a vertical plane, separate latching means for retaining each blade in the closed position, control means for releasing each latch means independently of the other latch means, link means interconnecting the cam means for all phases, said spring means for a released blade driving the cam means for the other blades to release them from their latch means independently of their control means, manually operable means for closing said blades, and reset means actuated by each blade to reset its latch means.

9. In a polyphase switch structure, in combination, a rotatable switch blade for each phase, spring means for rotating each blade in a horizontal plane, cam means for moving each blade in a vertical plane, latching means for retaining each blade in the closed position, control means for releasing each latch means independently of the other latch means, link means interconnecting the cam means for all phases, said spring means for a released blade driving the cam means for the other blades to release them from their latch means independently of their control means, manually operable means for closing said blades, ratchet means driven by said manually operable means, and means for disengaging said ratchet means from the manually operable means when the blades are closed.

10. In a polyphase switch structure for sectionalizing a transmission line connected to an automatic reclosing circuit breaker located remotely from the switch, in combination, a pivotally mounted switch blade for each phase, insulating means supporting the blades, a separate latching mechanism for retaining each blade in the closed position, spring means for opening each blade, a counting device operating at the potential of the transmission line for releasing each latching mechanism independently of the other latch mechanisms after a predetermined number of interruptions of the circuit breaker in close succession, mechanical means actuated by the spring means for a released blade for releasing the other blades from their latch mechanisms and manually operable means for closing said blades and storing energy in said spring means, each latch mechanism being reset by the closing of its blade.

11. In an isolating switch for sectionalizing a transmission line connected to an automatic reclosing circuit breaker located remotely from the switch, in combination, a pivotally mounted switch blade, insulating means supporting the blade, latching mechanism for retaining the blade in the closed position, spring means for opening the blade, a counting device operating at the potential of the transmission line for releasing said latching mechanism after a predetermined number of interruptions of the circuit breaker in close succession, manually operable means for closing the blade and storing energy in the spring means, ratchet means driven by said manually operable means to actuate the blade, and means for disengaging the ratchet means when the blade is closed, said latching mechanism being reset by said blade while it is being closed.

12. In an air-break switch for isolating a portion of a distribution system having an automatic reclosing circuit breaker therein, in combination, a switch blade, insulating means movably supporting the blade, spring means for opening the blade, latching means for retaining the blade in the closed position, control means comprising a counting device operating at the potential of the distribution system for mechanically releasing said latching means

after a predetermined number of interruptions of the circuit breaker in close succession, manually operable means for closing the blade and storing energy in said spring means, ratchet means driven by said manually operable means to actuate the blade, and means for disengaging the ratchet means when the blade is closed.

13. In an air-break switch for isolating a portion of a distribution system having an automatic reclosing circuit breaker therein, in combination, a switch blade, insulating means movably supporting the blade, spring means for opening the blade, latching means for retaining the blade in the closed position, control means mounted on insulating means and comprising a counting mechanism operating at the potential of the distribution system, said counting mechanism mechanically actuating said latching means to release the switch blade after a predetermined number of interruptions of the circuit breaker in close succession and during one of the interruptions, manually operable means for closing the blade and storing energy in said spring means, ratchet means driven by said manually operable means to actuate the blade, and means for disengaging the ratchet means when the blade is closed, said latching means being reset during the closing of said blade.

14. In an air-break switch for isolating a portion of a

distribution system having an automatic reclosing circuit breaker therein, in combination, a switch blade, insulating means movably supporting the blade, spring means for opening the blade, latching means for retaining the blade in the closed position, control means mounted on insulating means and comprising a counting mechanism operating at the potential of the distribution system, said counting mechanism mechanically actuating said latching means to release the switch blade after a predetermined number of interruptions of the circuit breaker in close succession and during one of the interruptions, manually operable means for closing the blade and storing energy in said spring means, ratchet means driven by said manually operable means to actuate the blade, means for disengaging the ratchet means when the blade is closed, and reset means actuated by said blade for resetting said latching means when the blade is closed.
